UNITED STATES PATENT OFFICE.

PERLEY R. GLASS, OF BROOKLINE, MASSACHUSETTS, ASSIGNOR TO UNITED SHOE MACHINERY CORPORATION, OF PATERSON, NEW JERSEY, A CORPORATION OF NEW JERSEY.

BUTTON-ATTACHING MACHINE.

1,399,762.

Specification of Letters Patent. Patented Dec. 13, 1921.

Application filed May 11, 1918. Serial No. 233,975.

To all whom it may concern:

Be it known that I, PERLEY R. GLASS, a citizen of the United States, residing at Brookline, in the county of Norfolk and State of Massachusetts, have invented certain Improvements in Button-Attaching Machines, of which the following description, in connection with the accompanying drawings, is a specification, like reference characters on the drawings indicating like parts in the several figures.

This invention relates to button attaching machines and the particular embodiment of the invention to be described is of that class of button attaching machines which is particularly adapted for handling eye shank shoe buttons and attaching them to work, such as the button fly of a shoe, by means of wire staples. It will be understood, however, that many features of the invention are not limited to this particular application, either as regards the particular form of button or the particular form of staple shown and described.

The general object of the invention is to improve the operation of button attaching machines in respect to speed, accuracy, and facility of operation, and, in particular, to improve the mechanism for combining buttons and fasteners in the desired relation as they are taken from their respective raceways and attaching them to the work.

Button attaching machines using a metallic fastener are usually provided with a driver and a coöperating anvil and the work is located in the machine by reference to the anvil. One object of the invention is to provide a machine in which the operator's view of the anvil is unobscured when the machine is in its stop position. In the illustrated construction, the fastener raceway and the button raceway are both laterally displaced from the anvil when the machine is started and the button raceway is movable to present its endmost button with its eye in alinement with the anvil.

An important feature of the invention consists in novel carrier mechanism organized to receive a fastener from the fastener raceway and position it over the anvil for removal by the driver. A further feature consists in the association of the same mechanism with the movable button raceway, the organization preferably including resilient means for positively positioning a fastener

in alinement with the eye of the endmost button.

Other features of the invention relate to the staple raceway and the transerrer mechanism associated therewith for removing the endmost staple and delivering it to the carrier mechanism associated with the button raceway. One feature of this general arrangement is to be recognized in the provision of novel means underlying the endmost fastener and constructed and arranged to support the fastener during removal from the raceway. As shown, this means comprises a transerrer constructed and arranged to support the lower extremity of the fastener positively against the action of gravity.

A specific embodiment of the invention will be described in the following specification and is illustrated in the accompanying drawings which show these and other features of the invention not specifically pointed out above. It will be understood, however, that this preferred embodiment is capable of modification and alteration without departing from the true scope of the invention.

In the drawings,—

Figure 1 is an elevation of the left hand side of the machine;

Fig. 2 is an angular perspective of a portion of the machine taken from the right hand side near the front;

Figs. 3 and 4 are angular views of opposite sides of the end of the button raceway shown in operative relation to the driver and anvil;

Fig. 5 is a front view of this mechanism with parts broken away;

Fig. 6 illustrates the staple retaining mechanism removed from the button raceway;

Fig. 7 is an angular view, from the rear, of the staple raceway and its associated transerrer;

Fig. 8 is an angular view, from the front, of a portion of the transerrer;

Fig. 9 is an enlarged view showing the relation of the driver to an attached button and staple when the staple is of a particular sort; and

Fig. 10 is a plan view, partly in section, of the ends of the button and staple raceways and the staple transerrer.

The illustrated machine has been designed particularly for use in attaching previously formed staples of the type shown in

the application of Frank Harmon, Serial No. 834,914, filed April 28, 1914, which matured into Patent No. 1,262,782 on Apr. 16, 1918, but it will be understood that the features of the invention are equally applicable to any other form of similar metallic fastener.

The moving parts of the machine are mounted upon a base 10 at the rear of which there is journaled a driving shaft 12 having a combined pulley and fly wheel 14 and provided with cams 16, 18 and 20. A lever 22 pivoted to the base of the machine has a driver 24 adjustably attached to its forward end and at its rear end is forked to surround a cam 20 by means of which the said driver is actuated in timed relation to the other parts of the mechanism. An anvil 26 is attached to the base of the machine in alignment with the driver and acts in the usual manner to clench the staple which has been driven through the work.

Staples are supplied to the attaching mechanism by means of a staple raceway 30 supported, for example, by an arm 32 in fixed position upon the machine. This raceway is here shown as designed for the particular type of staple covered by the above-mentioned application but it will be obvious that it could equally well be designed to carry any desired type of metallic fastener and could be supported in this or any other way. A suitable cover 34 of usual form may be provided over the raceway to prevent the staples from being displaced during the operation of the machine. The staples may be supplied to this raceway from any usual form of hopper, not shown. Adjacent to the delivery end of the raceway is a vertical plate 36 supported from the cover 34, which plate is spaced from the end of the raceway by a distance substantially equal to the thickness of the attaching staple, and, coöperating with the raceway and arranged for movement intermediate said wall and the end of the raceway, is a transferrer 40 which is adapted to be reciprocated in substantially a straight line by suitable mechanism, here shown as comprising a rod 42 supported upon pivoted links 44 from the base of the machine and connected for actuation in the desired sequence by the cam 16 upon the main shaft of the machine. The forward link 44 is mounted upon an eccentric stud 45 so that the exact position of the transferrer with relation to the other mechanism may be accurately and readily adjusted. The transferrer will be seen to comprise a supporting member 46 positioned adjacent to the end of the raceway at such a level that it will receive and support against the action of gravity a staple which has been forced off from the end of the raceway and is resting against the vertical plate 36 (see Fig. 10). The sup-

porting member 46 engages the staple along one of its major dimensions, in this instance its base. In connection with this supporting member 46 there is provided a pusher 48 adapted to engage the staple along another of its major dimensions, for example, along the side of one of its legs. This pusher 48 is preferably constructed as a thin plate whose thickness is approximately the same as that of the staple and is, therefore, approximately the same as the width of the space between the end of the staple raceway and the vertical wall 36. When in a position opposite the end of the raceway, it prevents the delivery of staples therefrom. As a matter of precaution, the pusher 48 is preferably resiliently attached to the transferrer 40 by being mounted upon a block 50 which is slidably held on the transferrer by a screw 52 working in a longitudinal slot 75 therein and is normally pressed to its forward position by a spring 54. This arrangement avoids any danger of breakage of parts in case one of the attaching staples should become caught or displaced during the operation of the machine.

Buttons are supplied to the attaching mechanism from a button raceway 60 which is constructed throughout a major portion of its length in the usual manner to receive the desired type of button and carry the same along to the attaching position upon its side so that it will be presented to the attaching mechanism with its eye in horizontal position to receive one leg of a staple forced into the work by the action of the driver 24. Certain features of this manner of presenting a button and of the illustrated form of driver, whereby the particular type of staple hereinabove mentioned, may be forced through the eye of a button and brought into close engagement with the upper surface of the work, have been described and claimed in the application of Frank L. Harmon, Serial No. 12,142, filed March 4, 1915, which matured into Patent No. 1,282,225 on Oct. 22, 1918, and it will be noted from Fig. 9 that the driver is so constructed that a projecting portion thereof engaging a shoulder at the upper end of the staple passes through the eye of the button and brings said shoulder into close engagement with the work. Buttons may be supplied to this raceway from any suitable hopper, not herein shown.

The button raceway 60 is movably mounted upon the base of the machine by means of pivoted links 62 and, as in the case of the transferrer, there is provision for adjustment of the position of the forward end of the raceway by means of an eccentric stud 63 forming a pivot for the forward link 62. In order to prevent lateral displacement of the forward end of the button raceway, the forward link 62 is guided 120

by means of a slotted plate 64 mounted upon the base of the machine. This raceway 60 is to be actuated at the desired time by means of a link and roller connection 66 to 5 the cam 18.

Buttons are temporarily retained in the raceway 60 by means of spring fingers 68 and 69 and, being disposed upon their sides, push the endmost button into the position, 10 best shown in Figs. 4 and 5, in which the eye of the button projects beyond a side plate 70 attached to the button raceway and, in the illustrated embodiment, beneath the lower edge of said plate. It will be noted 15 that the opposite face of the side plate 70 is in alignment with the vertical wall 36 arranged adjacent to the end of the staple raceway. Means are then provided for positioning the metallic fastener in predetermined relation to the endmost button in the raceway and these means comprise a carrier member 72 which, in the illustrated form, is attached to the button raceway by screws 20 74 and so shaped, in conjunction with one 25 face of the side plate 70, that a driver passage 76 is formed adjacent to the endmost button in the button raceway. Mounted upon the member 72 is a block 78 which is resiliently urged toward the side plate 70 30 by means of a leaf spring 80 acting upon studs 82 in the said block and passing through the member 72. These parts then constitute a carrier constructed and arranged positively and resiliently to retain 35 an attaching staple in predetermined relation to the driver passage and hence to the driver and the endmost button in the button raceway. The retaining member 78 is 40 preferably beveled upon its upper edge in order to facilitate entrance of the end of the driver 24 and again at one side to facilitate entrance of a staple delivered thereto by the transferrer 40 through a passage formed by a recess 84 in the block 72 on the side toward 45 the staple raceway. The retaining member 78 is also provided with a vertical groove 86 designed to receive one leg of the attaching staple and thus assist in positively retaining the same in position for removal by 50 the driver.

In operation, let us suppose that the button and staple raceways have been supplied with buttons and staples, respectively, and that the button raceway is in its rearmost position, indicated in Figs. 1 and 2, so that the carrier 72 is in position to receive a staple delivered thereto by the transferrer 40. This transferrer, with which the member 46 is supporting a staple between the end 55 of the raceway and the vertical wall 36, will, by the action of its pusher 48, force a staple through the recess 84 in the carrier 72 past the lateral beveled surface of the retaining member 78 to a position where its forward 60 leg is received in a groove 86 and such that

it is in alignment with the eye of the endmost button in the button raceway. For reasons already discussed in the application last mentioned above, the arrangement will be such that the leg of the staple received 70 in the groove 86 is disposed nearer to one side of the eye of the button instead of being directed toward its exact center. It will be noted that when the pusher 48 of the transferrer is moved forward to deliver 75 a staple to the retaining mechanism, it will occupy the space between the end of the raceway 30 and the vertical wall 36 and will, therefore, prevent other staples from falling from the end of the raceway. Even if it 80 did not occupy this space, however, the arrangement is such that the supporting ledge 46 would only allow one staple to pass from the end of the staple raceway. The trans- 85 ferrer will now recede and the raceway with its staple retaining mechanism will move forward into position adjacent to the anvil 26 so that the driver may enter the driver passage 76 in exact relation to the head of the attaching staple and, being forced 90 downward by its cam, may drive the staple through the eye of the button and the work and clench the same against the anvil 26 in the manner illustrated in Fig. 9. The button raceway, with the carrier 72 will then 95 be drawn backward and the endmost button pulled out of the raceway past the spring 68, it being held at this time by the co-operation of the driver 24 and the anvil 26. The work will then be moved forward into 100 position for a repetition of the cycle of operation.

Having thus described my invention, what I claim as new and desire to secure by Letters Patent of the United States is:

1. In a button attaching machine, a button raceway, a fastener raceway, and fastener transferring means for removing a fastener from the raceway and delivering it to other mechanism of the machine, said 105 transferring means being constructed and arranged to extend beneath the lower extremity of and to support said fastener during its removal from a position opposite the end of the fastener raceway.

2. In a button attaching machine, a fastener raceway, means for controlling the delivery of the fasteners from the raceway constructed and arranged to permit the passage of one fastener at a time, and transferring means for removing a fastener from the raceway and delivering it to other mechanism of the machine, said transferring means having a fastener-supporting element and an element for delivering a fastener 110 from the supporting element, said elements being movable together and being also arranged for independent movement to effect the delivery.

3. In a button attaching machine, a fas-

tenor raceway, stop means separated from the end of said raceway by substantially the thickness of a fastener, and transferring means entering the space between the stop means and raceway and underlying the end-most fastener, said transferring means being constructed and arranged to support said fastener during its removal from a position opposite the end of the fastener raceway.

4. In a button attaching machine, a fastener raceway, a stop plate separated from the end of the raceway by substantially the thickness of a fastener, a transerrer movable between said raceway and said plate and being provided with means for supporting a fastener during the time that it is being transferred, and a driver coöperating with the transferred fastener.

5. In a button attaching machine, a fastener raceway, means separated from the end of said raceway by the thickness of a fastener constructed and arranged to prevent the outward passage of a plurality of fasteners from the raceway, and movable means constructed and arranged for movement laterally between said raceway and said first mentioned means and beneath the fastener to remove said fastener laterally from the raceway and to support and deliver it to other mechanism of the machine.

6. In a button attaching machine, a raceway arranged to deliver button fasteners, fastener transferring means for removing a fastener from the raceway and delivering it with a button to other mechanism of the machine comprising means arranged to engage one side of a fastener during transference, and means held in resilient relation to move with said transferring means and arranged to engage the opposite side of the fastener during the transfer of the same.

7. In a button attaching machine, a raceway for staple fasteners, and transferring means for removing a fastener from the raceway and delivering it to other mechanism of the machine comprising means constructed and arranged to engage the fastener along two of its major dimensions, including the length of the staple legs.

8. In a button attaching machine, fastener driving mechanism, fastener supplying mechanism disposed at the side of the driving mechanism, movable means for presenting a button to the driving mechanism, and a carrier movable in the presentation of the button to present a fastener to the driving mechanism.

9. In a button attaching machine, fastener driving mechanism, fastener supplying mechanism, a movable button raceway constructed and arranged to present a button to the driving mechanism, and carrying mechanism movable with said button raceway constructed and arranged to transfer a fastener

from the fastener supplying mechanism to the driving mechanism.

10. In a button attaching machine, fastener driving mechanism, fastener supplying mechanism, a movable button raceway constructed and arranged to present a button to the driving mechanism, and a carrier in fixed relation to said button raceway and movable therewith constructed and arranged to receive a fastener from the fastener supplying mechanism and transfer it to the driving mechanism in fixed relation to the button to be delivered by the button raceway.

11. In a button attaching machine, fastener driving mechanism, fastener supplying mechanism disposed at the side of the driving mechanism, a movable button raceway constructed and arranged to present a button to the driving mechanism, and a carrier constructed and arranged to transfer a fastener from the fastener supplying mechanism to the driving mechanism.

12. In a button attaching machine, an anvil, button supplying mechanism and fastener supplying mechanism disposed beside said anvil, a carrier movable with the button supplying mechanism and constructed and arranged to receive a fastener from said fastener supplying mechanism and transfer it to a position in alinement with said anvil, and a driver constructed and arranged to remove the fastener from the carrier and clench it against the anvil thereby to attach a button to the work.

13. In a button attaching machine, an anvil, a coöperating driver movable toward and away from the anvil, a fastener raceway having its delivery terminal offset laterally from the line of movement of the driver, a button raceway terminating at one side of the anvil and movable to present its end-most button with its eye over the anvil, and carrier means for receiving a fastener delivered by the fastener raceway and delivering it in a position in alinement with the eye of the button so that it may be removed from the carrier means and driven through the eye of the button into the work by the driver.

14. In a button attaching machine, fastener driving mechanism, a fastener raceway, a carrier constructed and arranged to receive a fastener from the fastener raceway and move it into position for removal by the driving mechanism, and transerrer mechanism for removing a fastener from the fastener raceway and delivering it to the carrier mechanism, said transerrer mechanism being movable in the same direction as said carrier mechanism.

15. In a button attaching machine, an anvil, a fastener raceway, a carrier constructed and arranged to receive a fastener from the fastener raceway and move it into a position adjacent to said anvil, a transerrer

mechanism for removing a fastener from the raceway and delivering it to the carrier mechanism, and a movable button raceway constructed and arranged to bring its endmost button into position adjacent to the anvil with its eye in alignment with the fastener held in the carrier mechanism.

16. In a button attaching machine, a raceway for buttons provided with retaining means adjacent to its delivery end for supporting a button with its eye in projecting relation, and means for temporarily retaining a fastener in predetermined relation to the eye of the endmost button.

17. In a button attaching machine, a button raceway provided with a driver passage adjacent to its delivery end and with resilient means for positively positioning a fastener in a definite relation to said driver

20 passage in the raceway.

18. In a button attaching machine, a movable button raceway provided with a side plate and means for supporting the endmost button with its eye projecting beyond said side plate, and means carried by said raceway for supporting a fastener against said side plate in predetermined relation to the projecting eye of the endmost button in the raceway.

19. In a button attaching machine, an anvil, fastener carrier mechanism provided with retaining means having a groove for the reception of the shank of a fastener, and means for moving said carrier constructed and arranged to bring said groove and the eye of a button alined therewith over said anvil.

20. In a button attaching machine, a button raceway, and a fastener retaining device in said raceway comprising resilient means provided with a shallow groove in fixed relation to the eye of the endmost button in the raceway for the reception of a portion of a fastener held by said retaining device.

21. In a fastener inserting machine, fastener positioning mechanism having relatively fixed and movable walls, one of which is provided with a driver passage and with a passage for the admission of a fastener angularly related to said driver passage and comprising means situated in a wall of intersecting portions of the passages for positively positioning a fastener delivered thereto, a driver, and a fastener transferring device movable in a path intersecting the path of the driver.

22. In a fastener inserting machine, a spring pressed plate constructed and arranged to co-act with a fastener positively to position the same, said plate being beveled at one side to allow the ready admission of a fastener being delivered thereto and beveled upon another side to allow the ready admission of a driver for removing a fastener therefrom.

23. In a button attaching machine, attaching mechanism, button and fastener raceways, and means carried by the button raceway for positioning a fastener for co-operation with the attaching mechanism.

In testimony whereof I have signed my name to this specification.

PERLEY R. GLASS.
